CLAIM

The ornamental design for a bicycle rack, as shown and described.

DESCRIPTION

FIG. 1 is top, front, left side perspective view of a bicycle rack showing my new design in a first position;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a top, front, left side perspective view showing my new design in a second position;

FIG. 9 is a top, front, left side perspective view showing my new design in a third position; and,

FIG. 10 is a top, front, right side perspective view thereof, including additional unclaimed environmental features.

The broken lines of FIG. 10 form no part of the claimed design.
